(57) **CLAIM**

The ornamental design for a rehabilitation device, substantially as shown and described.

DESCRIPTION

FIG. 1 is a top isometric view of a rehabilitation device showing our new design.

FIG. 2 is a front view of the device of FIG. 1.

FIG. 3 is a rear view of the device of FIG. 1.

FIG. 4 is right side view of the device of FIG. 1.

FIG. 5 is a left side view of the device of FIG. 1; and, FIG. 6 is a top view of the device of FIG. 1.

The dashed lines form no part of the claimed design.
